Inventor

Ernest H. Goering
Sho. Stevens

Attorney

UNITED STATES PATENT OFFICE.

ERNEST H. GOERING, OF DULUTH, MINNESOTA.

DENTAL BRIDGE.

Application filed March 5, 1923. Serial No. 622,723.

To all whom it may concern:

Be it known that I, ERNEST H. GOERING, a citizen of the United States, residing at Duluth, in the county of St. Louis and 5 State of Minnesota, have invented certain new and useful Improvements in Dental Bridges, of which the following is a specification, reference being had therein to the accompanying drawing.

10 This invention relates to artificial teeth and has special reference to a novel form of tooth and bridge therefor.

The principal object of the invention is to provide a more practical, efficient, and 15 durable combination of this character than heretofore known.

Another object is to provide a form of 20 artificial tooth which may be readily fitted to the gums of the patient.

Other objects and advantages of the invention will appear in the further description thereof.

25 Referring to the accompanying drawing, forming part of this application and in which like reference characters indicate like parts:

Figure 1 is a fragmental portion of a bridge embodying my invention;

30 Figure 2 is a perspective view of one of the artificial teeth for the bridge;

Figure 3 is a front elevation of Figure 2; and

Figure 4 is a side elevation of a tooth as applied to a section of the bridge.

35 The bridge is composed of a plurality of metal U-shaped tooth receiving members or cups 1, each being sufficiently large to preferably encompass approximately one-fourth of the external area of a tooth and applicable thereto from the inside thereof.

Each cup 1 is formed adjacent its root or gum edge with an inwardly projecting reinforcement or ridge, which is generally 40 rectangular in cross section, the wall of the remainder of the cup being much thinner in construction but of such a shape externally as to conform with the shape of the artificial tooth and being flush therewith when assembled.

50 The tooth 3 has a cut-away portion or recess near the free end thereof, said recess being stepped, forming a deeper portion thereof nearest the base of the tooth indicated at 4 and into which the ridge 2 of the cup snugly fits. This deeper portion or

channel 4 is formed at a decided angle to the axis of the tooth so that it inclines outwardly from the axis of the tooth towards the base thereof, so that when the tooth is removed or applied to the cup it is accomplished by an oblique motion, it being essential that the end walls of the cup reach to a point on the artificial tooth beyond the vertical axis thereof so as to insure against breakage when axial stress is put upon the tooth.

From the above it is apparent that I have accomplished an exceedingly desirable union between the tooth and the bridge cup and one which during the process of mastications is improved rather than being jeopardized, as an axial thrust upon the tooth has a tendency to force it more tightly into the cup. The cups may be united as by soldering or the like, as at 5, as preferred in forming a bridge of any desired length and which may be supported upon crowns forming natural teeth as is common, though such abutments are not shown in the accompanying drawing.

In this combination of bridge and artificial tooth it becomes exceptionally advantageous to use a tooth having a fully formed root tip 6, and, as it is applied or removed from the bridge by a semi-vertical motion, it becomes exceptionally easy to fit same neatly to the natural contour of the gums by grinding off the tip to the desired form.

By this means it becomes more practical to manufacture the artificial teeth with fully or abnormally extended root tips thus avoiding the necessity of applying backing thereto as is commonly practiced. The teeth are designed to be made of porcelain in the usual manner and permanently secured within the bridge by means of cement as is common.

Having thus described my invention, what I claim and desire to secure by Letters Patent is:

1. The combination with a dental bridge having a metal tooth receiving cup, of an inwardly projecting inclined continuous ridge within said cup adjacent the base thereof, and an artificial tooth having an inclined recess about the inside wall thereof for cooperative engagement with the ridge within the cup and a stepped portion above the recess for overlapping engagement with the upper portion of the cup.

2. The combination with a dental bridge having a tooth receiving cup, of inwardly projecting means within said cup, said means being inclined downwardly towards
5 the innermost front wall of the cup, an artificial tooth having an inclined recess there-
in for cooperative engagement with the inwardly projecting means within the cup,
and a stepped portion above said recess for

overlapping engagement with the upper 10 portion of the cup.

In testimony whereof I hereunto affix my signature in the presence of two witnesses.

ERNEST H. GOERING.

Witnesses:

S. C. BRONSON,
S. Geo. STEVENS.
